UNITED STATES PATENT OFFICE.

JOSEPH ANTHONY GOOD, OF CHICAGO, ILLINOIS.

LIQUID-DISPENSER.

1,385,127.

Specification of Letters Patent. Patented July 19, 1921.

Application filed May 16, 1916. Serial No. 97,819.

To all whom it may concern:

Be it known that I, JOSEPH A. GOOD, a citizen of the United States, residing at Chicago, in the county of Cook and State 5 of Illinois, have invented certain new and useful Improvements in Liquid-Dispensers; and I do hereby declare the following to be a full, clear, and exact description of the invention, such as will enable others skilled 10 in the art to which it appertains to make and use the same.

This invention is a liquid dispensing device adapted more particularly for containing and dispensing ink and similar fluid 15 substances which are liable to readily evaporate and wherein it is desired to frequently obtain small quantities of the substance.

The object of the invention is to store a quantity of the fluid in a reservoir or 20 vessel which is substantially sealed against evaporation and the gathering of dust and dirt, and at the same time to provide a receiving receptacle or trough in which a small quantity of the fluid may be exposed 25 for ready use at a predetermined level, the fluid being passed from the reservoir to the receiving receptacle or trough by manually controlled devices. A further object of the invention is to provide a valve whereby the 30 fluid in the receiving receptacle or trough may be returned to the reservoir and the reservoir thereafter sealed to prevent loss of the substance by evaporation. Substantially all of the operable elements of the device 35 may be included in one body, whereby the cost of manufacture is materially reduced and the appearance and salability of the device is increased.

The device is simple in construction, durable and efficient in operation, the return 40 of the fluid to the reservoir from the receiving receptacle or trough operating to wash the trough by the flushing action of the fluid pumped back and forth through the 45 duct connecting the reservoir with the trough.

Other objects and features of novelty will 50 become apparent from the following detail description of the invention, taken in connection with the accompanying drawings and the appended claim.

While preferred embodiments of the invention are disclosed in the accompanying drawings, it is to be understood that the 55 constructions therein shown are for the pur-

poses of illustration only, and not as defining the limits of the invention.

In the drawings:

Figure 1 is a plan view of an ink well, disclosing the invention. 60

Fig. 2 is a sectional view on the line 2—2 of Fig. 1.

Fig. 3 is a detail sectional view of another form of device disclosing the rotatable valve positioned in the duct connecting the reservoir with the discharge trough. 65

Fig. 4 is a sectional view of another embodiment of the invention disclosing the top portion of the well and feed duct separate from the base of the well. 70

The device is shown applied to an ordinary ink well for dispensing ink from the reservoir or well proper to a pen-dip trough, or reservoir section, the well being provided with a resilient closure, which, when operated, acts upon the impounded air within the reservoir to press against the body of ink and force the ink from the reservoir through the duct to the pen-dip trough. 75 The supply of ink in the trough may be limited to a predetermined height by providing a break in the wall of the reservoir, whereby the fluid in the pen-dip trough may flow back into the duct and reservoir when the level of the fluid in the trough is higher 80 than that in the reservoir. Furthermore, the pen-dip trough may be washed by the fluid of the reservoir through means of a rotatable valve element positioned in the connecting duct and the manipulation of 85 the resilient element of the reservoir. 90

Referring more particularly to the embodiments of the invention set forth in the accompanying drawings, the base or a stand is indicated at 1, and, if desired, may be 95 provided with pen racks 2 and a recess 3. The base may be formed of a single piece of material, such as glass, and provided with a reservoir section in the form of a container indicated at 4, such reservoir section 100 being shown provided with a top 5 and bottom 6. The top 5 may be provided with a filling aperture 7, the wall of which terminates in an annular ring 8 to provide a recess for the reception of an end of a resilient member 9. This resilient member may be of any desired form and material, and in practice may be constructed in the form of a rubber cap, which is shown concavo-convex in form and provided with a 110

binding ring 10. The aperture 7 of the reservoir 4 may be provided also with a plate 11 to limit the compressing movement of the resilient element 9.

5 In the construction illustrated in Fig. 2, the base 1 is provided with an upstanding wall 12 which is broken intermediate its length and offset as at 13 to form an upper section 12^a of the wall with a passage 14 between the sections 12 and 12^a. The top 5 of the reservoir is shown provided with a depending wall 15 which extends from the top to substantially the base 6 of the reservoir, and forms a part of a discharge duct 16 for the reservoir.

10 Positioned adjacent the reservoir and formed by a base wall 17 and a side wall 18 is the receiving receptacle, which may serve as a pen-dip trough, the receptacle being indicated at 19. The bottom 17 of this receptacle is shown on a plane above that of the bottom 6 of the reservoir, and the aperture 14 between the wall sections 12 and 12^a may be on a plane above that of the liquid level in the reservoir, such liquid level being indicated by the line 20 in Fig. 2.

15 The upper end of the discharge duct 16 may be of greater area than that portion of the duct which connects the reservoir with the receiving receptacle 19, such enlarged portion being indicated at 21 in Fig. 2, and closed by a removable cap 22. This cap permits of the cleaning of the duct 16 and passage 14, should the flow of fluid from the reservoir to the receiving receptacle be impeded by the clogging of the duct by sediment due to evaporation of the fluid substance.

20 In the embodiment of the invention disclosed in Fig. 3, the wall 15 is shown extending to substantially the base 6 of the reservoir to form the duct 16, but the wall 12 of the reservoir is not shown offset to provide the end 12^a as in Fig. 2. In the duct 16 there is shown a rotatable valve element 45 having a head 23 and a hollow stem 24, said stem being provided with a port 25 near the head 23 and another port 27 near the lower end of the tubular end and opposite to the port 25. The wall indicated at 12^b is provided with a lower port 27^a which leads from the pen-dip trough 19 to the duct 16, on a level with the bottom 17 of said trough, and said wall 12^b is provided also with a 50 port 28 which registers with the upper port 25 of the rotatable valve 23.

25 When it is desired to supply ink to the pen-dip receptacle 19 and maintain it in the receptacle, the valve 23 is rotated to the position shown in Fig. 3 so that fluid from the reservoir may be forced, by operating the cap 9, through the duct 16, the tube 24 and the ports 25, 28 into the receptacle 19.

30 When the operator is through using the well 65 and desires to return the fluid to the reser-

voir, the valve 23 is rotated to the opposite position to that shown in Fig. 3 and so that the port 26 registers with the port 27, thereby permitting the fluid in the pen-dip trough 19 to flow from said trough through 70 the duct 16 and back into the reservoir. If it is desired to flush the pen-dip trough and wash said trough of any sediment which may have occurred in said trough, the valve 23 may remain in the latter position while 75 the resilient element 9 is depressed and raised slowly and successively to force fluid into the pen-dip trough 19 and permit it to flow out of the same until said reservoir becomes substantially free from sediment. 80 Thereafter, the valve may be rotated a quarter turn to move its ports 25, 26 out of register with the ports 27, 28 and operate to substantially seal the reservoir against the ingress or egress of fluid. The reservoir may 85 be filled by removing the cap 9, or in any other suitable manner.

35 Referring to the construction shown in Fig. 2, I may prefer to construct a device as shown in Fig. 4, wherein the base 1 is 90 provided with the reservoir section 4 and the receiving receptacle 19 positioned adjacent thereto, as previously described. In this construction the wall of the reservoir 4 may be of the same thickness and is indicated at 95 29, except for the front section of the wall which forms a part of the pen-dip 19 which is indicated at 30. This section of the wall 30 is shown slightly lower than the rear section 29.

40 Coöperating with the base 1 is a removable cover section which is provided with the usual top 5, having the annular ring 8 to receive a resilient or compressible member 9, as previously described. The top 5, 105 however, is shown provided with a flange 31, designed to rest upon the wall 29 and a depending flange 32 to bear against a side wall 29, it being understood that said wall 29 extends from the back to, and including 110 each side of the wall, if so desired. At the front part of the top, there may be formed a depending flange 33 to rest against the face of the wall 30, which is directed toward the pen-dip 19, and if desired, this section 115 of the top may be provided also with an interior flange 34 to rest against the opposite face of said wall 30. In the drawings there is shown a passage 35, formed in the flange 33 and through the front section of the top, said passage leading from the reservoir 4 to the pen-dip 19. It is preferred to connect said passage 35 with the lower portion or bottom face 6 of the reservoir 4, and to accomplish this purpose, there may be provided a tube 36 which communicates with the passage 35 and extends into closer proximity to the bottom wall 6 of the reservoir. By an inspection of Fig. 4, it will be understood that the compression of the member 120

9 will act upon the impounded air in reservoir 4 to force the fluid from said reservoir through the tube 36 and passage 35 into the pen-dip 19, as the fluid in the dip may be consumed.

Having thus described the invention, what is claimed as new and desired to be secured by Letters Patent of the United States, is:—

A device of the class described, comprising a reservoir, and a receptacle, a supply duct connecting the reservoir with said receptacle and provided with an inlet port

leading to the top of the receptacle and an outlet port leading to the bottom of the receptacle, a single valve mounted in the duct 15 adapted to close both ports or open one at will, and means to cause the contents of the reservoir to flow into the receptacle.

In testimony whereof, I affix my signature, in presence of two witnesses.

JOSEPH ANTHONY GOOD.
